CLAIM

The ornamental design for a spout, as shown and described.

DESCRIPTION

FIG. 1 is a perspective view of a spout. The spout may be removably attached to a bottle or other container. One example of the spout (e.g. bottle spout) is a funnel (e.g. a bottle funnel).

FIG. 2 is a rear view of the spout.

FIG. 3 is a front view of the spout.

FIG. 4 is a right side view of the spout.

FIG. 5 is a left side view of the spout.

FIG. 6 is a bottom plan top view of the spout; and,

FIG. 7 is a top plan view of the spout.

The features shown in broken lines in the various figures are for illustrating environmental structure and form no part of the claimed design.
